SPRINGING FOR RAILWAY TRUCKS

Isaac M. Chambers, Narberth, Pa.

Application June 12, 1940, Serial No. 340,027

10 Claims. (Cl. 105—197)

This invention relates to railway trucks and the like, and especially to springing suitable for bolster type trucks. An important aim of the invention is to provide a wider range of elasticity without necessity for making trucks larger than usual. The invention permits of a soft, yielding spring action for light loads, combined with a stiffer action for heavy loads. In suitable forms of embodiment, the invention allows of easy adjustment or replacement to take care of wear, and relatively low maintenance cost. The spring rigging can be made simple and rugged, and especially accessible for inspection or repair, as well as inexpensive to manufacture. The rate of deflection under light and heavy loads can readily be controlled and adjusted, and hammering under sudden overloads can be prevented. The action of the spring rigging can be made comparatively very quiet, and the transmission of vibration and shock to the lading minimized.

Other features and advantages of the invention will appear from the following description of species or forms of embodiment, and from the drawings. All the features and combinations illustrated or described are of my invention, so far as novel.

In the drawings, Fig. 1 is a plan view of one side of a railway truck conveniently embodying the invention, including the corresponding side frame and bolster end, certain parts being partly broken away or in section; Fig. 2 is a side view of the truck, certain parts being partly broken away; Fig. 3 shows a transverse section through the truck, taken as indicated by the line and arrows III—III in Fig. 1, on a larger scale; Fig. 4 shows a transverse section taken as indicated by the line and arrows IV—IV in Fig. 2, one of the parts shown in Fig. 2 being omitted; and Fig. 5 shows a section taken as indicated by the line and arrows V—V in Fig. 2.

Fig. 6 is a fragmentary side view of a truck similar to that shown in Fig. 2, illustrating a modification; and Fig. 7 is a corresponding fragmentary sectional view similar to Fig. 3.

The drawings show only one side of the truck, since the other side may be just like that illustrated. Accordingly, there is shown in Figs. 1 and 2 a side frame 10, resembling those of present standard freight car trucks in general design and construction, with one end of a transverse bolster 11 that carries the load of the car body, as usual. Besides the usual axle-box jaws or housings 12 with openings 13, the side frame 10 has the window opening 14 in the upper part of which the end of the bolster 11 is engaged and

guided for up and down movement relative to the frame. As shown in Fig. 1, the bolster end has vertical stop flanges 16, 16 which engage and coact with the usual guideways 17, 17 at opposite sides of the window opening 14, to determine the longitudinal position of the bolster 11 in the window 14, and to keep the side frame 10 truly upright. Above and below the window 14 are the usual top and bottom side frame members 18, 19.

Two types of springing are here shown, which in practice are preferably used in conjunction with one another: viz., a torsional type of spring 20, and a cushion type of spring 21. Each cushion spring 21 is preferably arranged under the bolster 11, and (especially in the absence of a spring plank, which is not here shown) in the window 14, on the bottom member 19 of the side frame. The torsion spring 20, however, need not be limited in size, capacity, and range of deflection by the restricted dimensions of the window space. Such torsion springs 20 may be arranged lengthwise of the truck, alongside the side frames 10,—preferably at the outer side of the latter, as illustrated in Figs. 1 and 2. With this arrangement, the whole length of the side frame 10 is available to accommodate and mount the springs 20, which may thus be made of ample strength and elasticity.

As shown in Fig. 1, the spring 20 consists of a long torsion member having its ends anchored to the ends of the side frame 10 outside of or beyond the axle-box housings 12, 12, as by engagement in bracket-hubs 23 which are shown as integrally attached to the ends of the side frame 10, while the mid-portion of the member 20 is connected to the end of the bolster 11 at, in, or through the window 14. For this purpose, there is shown in Figs. 2 and 3 a crank-arm 25 whose hub 26 surrounds and is anti-turningly connected or engaged with the mid-portion of the torsion member 20, and whose free end 27 engages under or in the end of the bolster 11. Thus the two ends of the torsion member 20 are oppositely twisted under the load of the bolster. As shown in Figs. 1 and 2, diametral pins 28 normally extend across the otherwise open outer ends of the bracket hubs 23, to prevent endwise displacement of the torsion member 20, but may be removed to permit withdrawal of the member 20 from the bracket and crank hubs 23, 26, 23. As shown in Figs. 1, 2, and 3, the torsion member 20 is of rectangular section, and the openings for it in the hubs 23, 26, 23 are correspondingly shaped, to give effective anti-turning engagement or keying of the member in these hubs.

Thus no special work on the torsion member 20 is required to provide for its anti-turning engagement or anchorage in the parts 23, 26, 23. While preferably in a single length from one anchorage 23 to the other, as shown in Fig. 1, the torsion bar 20 may if desired be made in two sections abutting endwise in the middle of the crank hub 26, as indicated in Fig. 2.

Preferably, the torsion member 20 is of laminated construction, (rather than a mere one-piece bar), consisting of a bundle or "pile" of superposed spring strips 29, Figs. 1, 3, 4 and 5. This laminated construction of the torsion member 20 has the advantage that the strips 29 are relatively thin and can be better heat-treated than a solid bar could be, so as to have superior elastic qualities. Also, the laminated bar will twist more under a given torque and bolster load than would a single solid bar of the same cross-section.

Bearing may be provided on the side frame 10 for sustaining the mid-portion of the torsion member 20 against deflecting downward under the bolster load, as by means of integral supporting or bearing brackets 30, 30 projecting outward from the frame at either side of the crank-arm 25. For this purpose, as shown in Fig. 2, the crank-arm hub 26 has hollow trunnions 31, 31 journaled in the bearing brackets 30, 30. In the present instance, the anti-turning or torque-transmitting connection of the member 20 to the crank 25, is made directly to the crank-hub 26,—the trunnions 31, 31 being of larger internal bore than the greatest cross-dimension of the member 20, so that the crank trunnions 31, 31 do not transmit the torque at all, but merely serve to sustain the middle of the member 20. As shown in Figs. 2, 3, and 4, the supporting brackets 30, 30 have removable bearing blocks 32, 32 with substantially semi-circular bearing surfaces for the trunnions 31, 31, and the trunnions 31, 31 have corresponding removable semi-circular wear plates 33, 33. The brackets 30, 30 are shown provided with seats for the trunnion bearings 32, 32 which are open transversely of the trunnion axes, in an upward direction, so that the bearings can be removed from said seats by a corresponding movement. As shown in Fig. 3, the crank-arm 25 has a recess 34 provided with a renewable wear-block 35 at its bottom, cylindrically concaved about an axis fore and aft of the truck, and the end of the bolster 11 has a corresponding flat-surfaced renewable wear block 36. Housed and held in the crank-end recess 34 is a roller 37 (with axis fore and aft of the truck), interposed between the wear-blocks 35, 36.

Connecting the supporting brackets 30, 30 there is a fore-and-aft web 38 of L-shaped cross-section, and at the outer ends of the brackets 30, 30 are transverse webs 39, 39, Fig. 4, with round holes 40, 40 therein for the torsion member 20. A removable sheet metal cover 41 coacts with the parts 30, 38, 39 to form a housing for enclosing the crank 25 with its trunnions 31, 31 and their bearings 32, 32, and protecting them from dust and dirt. As shown in Figs. 2 and 3, the upper and lower edges of the cover 41 are secured to the web 38 and to the side frame top member 18 by screws 42. Sheet metal or leather covers 43, 43 fitted to the torsion member 20 cover the holes 40, 40 to exclude dust and dirt from the bearings at 32, 32.

As shown in Figs. 1 and 2, the spring strips 29 are held together securely by clips or clamps 75

400 mounted on them between the supporting brackets 30, 30 and the end-anchorage hubs 23, 23. As shown in Fig. 5, the clips 400 consist of integral rectangular metal straps or "boxes" provided with elastic (rubber) pads 420, metal backing plates 430, and shake-proof set-screws 44 taking through the clips and bearing against the plates 430, so as to clamp the spring strips 29 tightly together.

As shown in Figs. 2 and 3, the cushion spring 21 is of highly elastic material, preferably suitably vulcanized rubber, and consists of a massive molded rubber block or buffer resting on the lower side frame member 19 that forms the bottom of the window opening 14. Sheet metal shims or spacers 45 are interposed between the rubber cushion 21 and the side frame member 19, for a purpose to be explained hereinafter. The rubber cushion or spring 21 is preferably held in place by a surrounding metal frame or housing 46 bolted to the member 19 around the base of the spring block 21, through the spacers 45. The base of the rubber cushion 21 has a shouldered flange 47 that engages in a correspondingly shouldered rabbet of the housing 46. Above the base of the cushion 21, the wall of the housing 46 diverges from the cushion 21, thus affording some clearance for outward expansion of the rubber. As here shown, this divergence results partly from an inward concavity of the cushion sides, and partly from an outward flare of the housing wall, on a curvature which increases upward and merges at the top of the housing into a rounded lip 48.

The diverging housing 46 around the cushion 21 allows lateral outward expansion of the cushion when it compresses vertically under the load of the bolster 11, yet also limits and controls the lateral expansion and the flow of the compressed rubber. To allow some lateral expansion of the rubber in the base of the cushion 21, notwithstanding the normally close engagement of the housing 46 around it, the cushion block is shown with a narrow but deep longitudinal cavity 49 extending upward into it from its bottom surface. As shown, the top or loading surface of the rubber cushion 21 is cylindrically rounded (about an axis fore and aft of the truck), so that its rate of deflection under the bolster load diminishes progressively until it becomes engaged with the bolster 11 over its own full width. This and the control of the cushion expansion by the flared housing 46 give a gradual build-up in the load capacity of the cushion: i. e., a diminishing rate of deflection relative to load. Even under sudden heavy overload, the cushion 21 will not go solid (like a metal spring), nor allow the bolster 11 to bottom or hammer against the cushion housing 46.

As shown in Figs. 2 and 3, there is an interval h between the top loading surface of the cushion spring 21 and the coacting bottom surface of the bolster end 11, so that the spring 21 does not come into action until the torsion spring 20 has deflected more or less. This interval h can be varied and regulated by increasing or reducing the number and thickness of the spacers 45; and thus the spring action can be made easier or stiffer, as desired. It can also be varied, of course, by changing the torsion spring 20, or by changing the hardness or the shape of the rubber spring 21. The action of both the springs 20 and 21 is naturally very quiet, and the rubber spring 21 has a large ability to absorb vibration and shock, and to minimize their transmission to

the lading of a car equipped with such springing.

Figs. 6 and 7 illustrate a construction like that of Figs. 1-5 in which a spring cushion 21a whose elastic rubber is in shear replaces the cushion 21 of Figs. 1-3, which is in compression. This cushion 21a comprises a series or pack of upright elastic rubber cushion strips 52 extending lengthwise of the truck in the window opening 14 of the side frame 10, alternating with relatively thin upright metal abutment strips. As shown, there are metal strips 53 at the outer sides and in the midst of the pack, resting on the bottom frame member 19a, and between adjacent strips 53 there are other metal strips 54 whose upper edges are arranged to engage the bottom of the bolster 11, and may be thickened or headed as shown to prevent them from slipping downward between the rubber strips 52. Also, the faces of the rubber strips may be cemented or vulcanized to the abutting surfaces of the metal strips 53, 54. When the cushion 21a is unstressed, as shown, the lower edges of the strips 54 are spaced a suitable height above the bottom of the bolster window, to allow adequate deflection of the cushion 21a under the bolster load. Preferably the edges of the rubber strips 52 are reduced or bevelled toward the metal strips 54, as shown. The cushion 21a is preferably enclosed and held upright in a metal housing 46a between whose sides it fits snugly (but not tightly), and spacing shims 45 are shown interposed between the housing 46a and the cushion 21a and the bottom side-frame member 19a. When the descending bolster 11 engages and depresses the metal parts 53, 54, the rubber strips 52 undergo a sort of shearing and bending deformation, accompanied by compression between the sides of the housing 46a, which resist expansion of the cushion 21a as the latter is deformed under the bolster load. Thus the cushion 21a powerfully resists deflection and deformation.

Various parts and features shown in Figs. 6 and 7 are marked with the same reference characters as the corresponding parts in Figs. 1-3, (with addition of a letter where such distinction appears necessary) as a means of dispensing with repetitive description.

Having thus described my invention, I claim:

1. In a truck of the character described, the combination with a side frame having provision for mounting the truck axles and wheels, and also having a window opening, and a load-sustaining bolster movable up and down relative to said side frame in said window opening, of a longitudinal elastic torsion member extending lengthwise of the truck and anchored to said side frame against turning; means for connecting said torsion member to the bolster at a substantial distance from the anchorage of said torsion member to the side frame, and thus elastically transmitting the load on the bolster to the side frame through said torsion member; and a spring cushion in the window opening of said side frame under the bolster, for engaging the bolster and coacting with said torsion member in elastically transmitting the load on the bolster to the side frame.

2. In a truck of the character described, the combination with a side frame having provision for mounting the truck axles and wheels, and also having a window opening, and a load-sustaining bolster movable up and down relative to said side frame in said window opening, of a

longitudinal elastic torsion member extending lengthwise of the truck and anchored to said side frame against turning; means for connecting said torsion member to the bolster at a substantial distance from the anchorage of said torsion member to the side frame, and thus elastically transmitting the load on the bolster to the side frame through said torsion member; and an elastic rubber cushion in the window opening of said side frame under the bolster for sustaining the latter and coacting with said torsion member in elastically transmitting the load on the bolster to the side frame.

3. In a truck of the character described, the combination with a side frame having provision for mounting the truck axles and wheels, and also having a window opening, and a load-sustaining bolster movable up and down relative to said side frame in said window opening, of a longitudinal elastic torsion member extending lengthwise of the truck and anchored to said side frame against turning; means for connecting said torsion member to the bolster at a substantial distance from the anchorage of said torsion member to the side frame, and thus elastically transmitting the load on the bolster to the side frame through said torsion member; an elastic rubber cushion in the window opening of said side frame under the bolster for sustaining the latter and coacting with said torsion member in elastically transmitting the load on the bolster to the side frame; and a housing around said rubber cushion affording clearance for limited lateral expansion of the latter concurrently with its yielding under the load on the bolster, but thereafter confining said cushion and thus controlling its further expansion and yielding.

4. In a truck of the character described, the combination with a side frame having provision for mounting the truck axles and wheels, and also having a window opening, and a load-sustaining bolster movable up and down relative to said side frame in said window opening, of a longitudinal elastic torsion member extending lengthwise of the truck and anchored to said side frame against turning; means for connecting said torsion member to the bolster at a substantial distance from the anchorage of said torsion member to the side frame, and thus elastically transmitting the load on the bolster to the side frame through said torsion member; an elastic rubber cushion in the window opening of said side frame under the bolster for sustaining the latter and coacting with said torsion member in elastically transmitting the load on the bolster to the side frame; and a housing engaged around the base of said rubber cushion to hold it in place, while thereabove diverging around the cushion, when the latter is unstressed, to permit lateral expansion of the cushion when it yields under stress due to increasing load on the bolster, but under heavier bolster loads confining the cushion and thus controlling its expansion and yielding.

5. In a truck of the character described, the combination with a side frame having provision for mounting the truck axles and wheels, and also having a window opening, and a load-sustaining bolster movable up and down relative to said side frame in said window opening, of a longitudinal elastic laminated torsion member, consisting of a bundle of superposed spring strips, extending lengthwise of the truck and anchored to said side frame against turning; means for connecting said torsion member to the bolster

at a substantial distance from the anchorage of said torsion member to the side frame, and thus elastically transmitting the load on the bolster to the side frame through said torsion member; and a spring cushion in the window opening of said side frame under the bolster, for engaging the bolster and coacting with said torsion member in elastically transmitting the load on the bolster to the side frame.

6. In a truck of the character described, the combination with a side frame having provision for mounting the truck axles and wheels, and also provided at its cuterside with lateral bearing and anchorage brackets at a substantial distance apart, and a load-sustaining bolster associated with said side frame and movable up and down relative thereto; of a longitudinal elastic laminated torsion member consisting of a bundle of superposed spring strips extending along the outside of said side frame in its said bearing and anchorage brackets, and anchored by the latter against turning, and a crank attached to said torsion member extending inward therefrom into position for engaging the bolster; and anchorage means for said torsion member attached to the side frame at a substantial distance from said crank, whereby the load on the bolster is elastically transmitted to the side frame through said torsion member.

7. In a truck of the character described, the combination with a side frame having provision for mounting the truck axles and wheels, and also having a window opening, and a load-sustaining bolster movable up and down relative to said side frame in said window opening, of a crank having trunnions, and itself extending into said window opening to engage the bolster to sustain the same; a longitudinal elastic torsion member extending along the outside of said side frame through said crank and its trunnions, and anti-turningly engaged in said crank; supporting brackets for said crank trunnions on the outer side of said side frame, at either side of its said window opening, having bearing seats that open transversely of the trunnion axes, and bearings for said trunnions seated in said bearing seats, and removable therefrom by a corresponding movement and anchorage means for said torsion member attached to the side frame at a substantial distance from said crank, whereby the load on the bolster is elastically transmitted to the side frame through said torsion member.

8. The invention as set forth in claim 7 further

comprising a housing for said crank, trunnions, and bearings including a cover removably mounted on said side frame.

9. In a truck of the character described, the combination with a side frame having provision for mounting the truck axles and wheels, and also having a window opening, and a load-sustaining bolster movable up and down relative to said side frame in said window opening, of a longitudinal elastic torsion member extending lengthwise of the truck and anchored to said side frame against turning; means for connecting said torsion member to the bolster at a substantial distance from the anchorage of said torsion member to the side frame, and thus elastically transmitting the load on the bolster to the side frame through said torsion member; and an elastic cushion in the window opening of said side frame under the bolster, for sustaining the latter and coacting with said torsion member in elastically transmitting the load on the bolster to the side frame, comprising a pack of rubber cushion strips and interposed abutments, part of said abutments resting on the bottom of the bolster window, while the rest of them are spaced therefrom and arranged to engage the bolster.

10. In a truck of the character described, the combination with a side frame having provision for mounting the truck axles and wheels, and also having a window opening, and a load-sustaining bolster movable up and down relative to said side frame in said window opening, of a longitudinal elastic torsion member extending lengthwise of the truck and anchored to said side frame against turning; means for connecting said torsion member to the bolster at a substantial distance from the anchorage of said torsion member to the side frame, and thus elastically transmitting the load on the bolster to the side frame through said torsion member; an elastic cushion in the window opening of said side frame under the bolster, for sustaining the latter and coacting with said torsion member in elastically transmitting the load on the bolster to the side frame, comprising a pack of rubber cushion strips and interposed abutments, part of said abutments resting on the bottom of the bolster window, while the rest of them are spaced therefrom and arranged to engage the bolster; and a housing around said elastic cushion resisting expansion of said elastic cushion strips as the bolster load deforms the cushion.

ISAAC M. CHAMBERS.
